(57) **CLAIM**

The ornamental design for a hair curler, as shown and described.

DESCRIPTION

FIG. 1 is a front perspective view of a hair curler, showing my new design.

FIG. 2 is a front view thereof.

FIG. 3 is a rear view thereof.

FIG. 4 is a left side view thereof.

FIG. 5 is a right side view thereof.

FIG. 6 is a top view thereof.

FIG. 7 is a bottom view thereof.

FIG. 8 is a rear, left perspective view thereof.

FIG. 9 is an enlarged detail view of area 9 shown in FIG. 1.

FIG. 10 is an enlarged detail view of area 10 shown in FIG. 2; and,

FIG. 11 is an enlarged detail view of area 11 shown in FIG. 4.

In the drawings, the broken lines illustrate enlarged view indicators and form no part of the claimed design.

In the drawings, the broken lines illustrate portions of the article which form no part of the claimed design.
